UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

VACUUM TUBE.

Application filed April 15, 1921. Serial No. 461,727.

To all whom it may concern:

Be it known that I, WILLIAM G. Hous-
keeper, a citizen of the United States, re-
siding at New York city, in the county of
5 New York, State of New York, have in-
vented certain new and useful Improve-
ments in Vacuum Tubes, of which the fol-
lowing is a full, clear, concise, and exact de-
scription.

10 This invention relates to a suspension de-
vice and has particular reference to a device
for supporting an electrode of a vacuum
tube.

The object of this invention is to provide
15 a resilient electrode supporting element of
a simple design and so constructed as to
permit ready adjustment of the electrode
during assembly of the tube and the con-
stant maintenance thereafter of said elec-
20 trode under uniform tension.

This object is attained by providing a
25 resilient member adapted to engage a mem-
ber rigidly supported within the tube and providing in combination with said resil-
ient member a portion to embrace and
firmly grip a suspension element. The elec-
trode to be supported is engaged with the
30 suspension element and the resilient portion
maintains the electrode under uniform ten-
sion.

This invention will be better understood
35 by having reference to the following spec-
ification and the accompanying drawing
wherein Fig. 1 is a side view partially
broken away of a vacuum tube embodying
the invention and Fig. 2 is an enlarged de-
tail of the suspension device.

A vacuum tube 1 is provided with a re-
entrant stem 2 on which is arranged a col-
40 lar 3 having arms 4 extending therefrom
into the interior of the tube. Carried by
the inner ends of the arms 4 is a substan-
tially cylindrical anode 5 to which are
welded rods 6. Carried by the ends of the
45 rods 6 are the lower and upper lavite blocks
7 and 8 between which is arranged the grid
electrode 9. Extending upwardly from the
lower block 7 and rigidly mounted therein
are the hooks 10. In the upper block 8
50 are provided apertures 11, the upper part
of which are countersunk as at 12. Ar-
ranged in each countersunk portion 12 is a
resilient support which comprises a loosely
wound wire helix 13 of a diameter approx-

imately the same as that of the countersunk
socket 12. Integral with the helix 13 is a
closely wound wire helix 14 of considerably
smaller diameter than the helix 13. The
shank of the hook 15 extends through the
55 aperture 11 and the helices 13 and 14, the
helix 14 closely embracing the shank. That
portion of the shank arranged within the
helix 14 and the helix itself are crimped to
provide a tight connection between them.
The cathode 16 is strung between the hooks
60 10 and 15 and is maintained under uniform
tension by means of the springs 13.

In the assembling of this structure, the
hooks 15 are engaged with the upper loops
65 of the cathode 16 and the suspension mem-
bers are arranged with the helices 14 embrac-
ing the shanks thereof. The hooks are
pulled up until the cathode is taut; the
springs 13 are then compressed after which
70 the helices 14 and the hook shanks are
crimped together. Any desired tension may
be obtained on the cathode by crimping the
helices 14 to the hook shanks at the proper
75 places.

Since the helices 13 are seated in the sock-
ets 12 the suspension members are main-
tained coaxial with the shanks of the hooks
80 15 and the possibility of the shanks bind-
ing in the apertures 11 is eliminated. Also
the full force of the spring is effective in
keeping the cathode under tension.

What is claimed is:

1. In combination, a suspension element
and a support therefor comprising a resil-
ient portion and a portion embracing said
suspension element, said embracing portion
and suspension element being crimped to-
85 gether.

2. In combination, a suspension element
and a support therefor comprising a helical
spring portion and a portion embracing said
suspension element, said embracing portion
and said suspension element being crimped
95 together.

3. In combination, a suspension element
and a support therefor comprising a helical
resilient portion and a portion embracing
said suspension element, said embracing portion
being rigidly connected with said sus-
pension element.

4. In combination, a suspension element
and a support therefor comprising a loosely
wound wire helix, and a closely wound wire

- helix integral therewith, said closely wound helix embracing said suspension element and being rigidly joined thereto.
5. A suspension device comprising a large diameter loosely wound wire helix, a small diameter closely wound wire helix integral therewith and a suspension element embraced by said smaller diameter helix and rigidly attached thereto.
10. 6. A suspension device comprising a large diameter loosely wound wire helix, a small diameter closely wound wire helix integral therewith and a suspension element supported by said smaller diameter helix.
15. 7. A suspension device comprising a large diameter loosely wound wire helix, a small diameter closely wound wire helix integral therewith and a suspension element passing through said helices and supported by said 20 small diameter helix.
8. A suspension device comprising a large diameter loosely wound wire helix, a small diameter closely wound wire helix integral therewith and a suspension element passing 25 through said helices and rigidly attached to said small helix.
9. A suspension device comprising a large diameter loosely wound wire helix, a small diameter closely wound wire helix integral 30 therewith, a suspension element passing through said helices, said small diameter helix and said suspension element being crimped together.
10. In combination, a suspension element 35 and a support therefor comprising a resilient portion surrounding said suspension element and a portion embracing said suspension element, said embracing portion and said suspension element being crimped together.
11. In a vacuum tube, a plate having an aperture therethrough, a suspension element 40 slidably arranged in said aperture, a support therefor comprising a resilient portion in contact with said plate, and a portion embracing and gripping said suspension
- element, said resilient portion being maintained against lateral movement.
12. In a vacuum tube, a plate having an aperture therethrough, a suspension device 45 comprising a large diameter loosely wound wire helix in contact with said plate, a small diameter closely wound wire helix integral therewith, a suspension element slidably arranged in said aperture, said suspension element being firmly embraced by said small diameter helix, and means for preventing lateral movement of said large diameter helix.
13. In a vacuum tube, a plate having a 50 countersunk aperture therethrough, a large diameter loosely wound wire helix arranged in said countersunk portion, a small diameter closely wound wire helix integral with said first helix, and a suspension element 55 slidably arranged in said aperture, said suspension element and said small diameter helix being crimped together.
14. In a vacuum tube, a plate having an aperture therethrough, a suspension element 60 slidably arranged in said aperture, an electrode supported by said suspension element, a support for said suspension element comprising a large diameter loosely wound wire 65 helix, a closely wound small diameter wire helix integral therewith, both of said helices surrounding said suspension element, the larger diameter helix being in contact with said plate and the suspension element and small diameter helix being crimped together.
15. In a vacuum tube, a plate having a countersunk aperture therethrough, a loosely wound wire helix arranged in said countersunk portion, a smaller diameter 70 closely wound wire helix integral therewith, a suspension element slidably mounted in said aperture and connected to said smaller diameter helix, and a cathode supported by 75 said suspension element.
- In witness whereof, I hereunto subscribe my name this 12th day of April A. D., 1921.
- WILLIAM G. HOUSKEEPER.
